UNITED STATES PATENT OFFICE.

WILLIAM A. MERRALLS, OF SAN FRANCISCO, CALIFORNIA.

ROCK BREAKER AND PULVERIZER.

No. 827,745.

Specification of Letters Patent.

Patented Aug. 7, 1906.

Application filed March 27, 1905. Serial No. 252,292.

To all whom it may concern:

Be it known that I, WILLIAM A. MERRALLS, a citizen of the United States, residing at San Francisco, in the county of San Francisco, 5 and State of California, have invented certain new and useful Improvements in Rock Breakers and Pulverizers, of which the following is a specification.

This invention relates to improvements in rock breakers and pulverizers, and is an improvement on the style of rock-breaker known as the "Nichols" rock-breaker, for which a patent was granted June 22, 1886, No. 344,004. This rock-breaker, although 15 an excellent rock-breaker when new, has never come into extensive use on account of the trouble it has given when it has been used a sufficiently-long time for some of the parts to wear. In said rock-breaker the ball-race 20 is formed in the crushing-cylinder, and the clutch is furnished by means of said ball-race and wedge-shaped projections formed on the inner faces of the sides of the frame, the balls being gripped between said sides and frame 25 and the ball-races in the cylinder. Should a ball-race wear irregularly or should it not be perfectly true in the first instance, this will cause fracture of the ball. When the ball fractures, instead of permitting the crushing- 30 cylinder to roll around, as it should, said cylinder stands in one place and the vertically-reciprocating crushing-jaw then impinges all the time against one part only of the crushing-cylinder, wearing it flat, and the machine 35 then becomes absolutely worthless until a new crushing-cylinder is substituted. To remove this cylinder, the shaft thereof has to be driven out longitudinally, and this is a slow and expensive operation. Moreover, the cylinder has to be entirely thrown away, which 40 is a very great waste of metal. These objections to its practical use have been so serious that very few were sold during the life of the patent.

45 The object of the present invention is to provide a construction which will render the above form of rock-breaker practical and successful.

In the accompanying drawings, Figure 1 is 50 a perspective view of my improved rock-breaker. Fig. 2 is a vertical section thereof on a somewhat larger scale. Fig. 3 is a vertical section through the grip. Fig. 4 is a cross-section of the grip on the line A A of

Fig. 3. Fig. 5 is a broken longitudinal section through the crushing-cylinder. Fig. 6 is a detail of a modified form of grip.

Referring to the drawings, 1 represents the frame of the rock-breaker, in which is mounted an eccentric shaft 2, carrying the usual fly-wheels and pulleys. The concave crushing-jaw 3 has its upper end eccentrically supported on said shaft, as shown at 4 in Fig. 2. In the face of said jaw is secured the crushing-plate 5, the crushing-face of which is corrugated horizontally or flat or any shape. At the rear of the lower end of said crushing-jaw is a bearing-block 6, which receives the front edge of the support-plate 7, the rear edge of which is received in a bearing-block 8, adjustably supported by means of plates 9. A hook 10 is attached to the rear side of the crushing-jaw and is drawn backward by means of a compressed spring 11.

The crushing-cylinder 12 is made with a main body 13, keyed on the shaft 14, and an external shell 15, held in place by bolts 16, having one-sided heads which overlie a circular shoulder on the shell and are secured by the nuts 17. For the purpose of preventing reverse movement of the crushing-cylinder said shaft is extended through bearings in the frame, and upon each end thereof is secured a grip-wheel 18, preferably grooved, as shown at 19. Said wheels turn adjacent to curved bearing-plates 20, formed upon standards 21, removably secured, as shown at 22, to the frame 1 of the machine. These bearing-plates are curved, as shown at 23, to form channels for the balls 24, retained therein by end plates 25. These grooves or channels decrease in depth from the upper to the lower portion, so that the bottom of the groove at the lower portion thereof approaches more nearly to the grip-wheel than at the upper portion. The consequence is that upon any reverse movement of the crushing-cylinder the balls are immediately gripped between said grip-wheels and bearing-plates, said balls at all times falling down in the grooves of the grip-wheels and bearing-plates as far as possible.

In Fig. 6 is illustrated a modification in which the grip-wheel is formed with ratchet-teeth 26, engaged by a pawl 27. The advantages of this construction are that there is no wear on the crushing-cylinder that is due to the operation of gripping to prevent the re-

verse movement. The wear is entirely upon the auxiliary grip-wheels, the balls, and the bearing-plates. All of these parts can easily be removed and replaced by new ones at 5 very slight expense, and also very quickly, which is an important consideration in mill-work. The balls are not now gripped between the crushing-cylinder and the sides of the frame, exerting a longitudinal pressure 10 upon said cylinder and frame, but are gripped between the auxiliary grip-wheels and the bearing-plates, exerting a radial pressure therebetween. It is to be understood that instead of the balls here shown the usual 15 equivalents thereof, rollers or other devices that will turn by friction, may be substituted.

I claim—

1. A rock-breaker, comprising a rocking jaw, a cylinder in front of said jaw, bearings 20 in which said journal is revolvably supported, a grip-wheel on the shaft of said cylinder outside one of said bearings, a grip member having a track which converges downward toward said wheel, and a rolling-grip carried by 25 said track, as set forth.
2. A rock-breaker, comprising a rocking jaw, a cylinder in front of said jaw, bearings 30 in which said journal is revolvably supported, a grip-wheel on the shaft of said cylinder outside one of said bearings, said wheel having a 35 peripheral groove, a grip member having an

inclined track, and a rolling-grip carried by said track, as set forth.

3. A rock-breaker, comprising a rocking jaw, a cylinder in front of said jaw, bearings 35 in which said journal is revolvably supported, a grip-wheel on the shaft of said cylinder outside one of said bearings, said wheel having a peripheral groove, a grip member having an inclined track, and a spherical ball carried by 40 said track, as set forth.

4. A rock-breaker, comprising a rocking jaw, a cylinder revolvably supported in front of said jaw, a grip-wheel on the shaft of said cylinder, a grip member having an inclined 45 track, and rolling-grips of different size carried by said track, as set forth.

5. A rock-breaker, comprising a rocking jaw, a cylinder revolvably supported in front of said jaw, a grip-wheel on the shaft of said 50 cylinder, said wheel having a peripheral groove, a grip member having an inclined track, and spherical balls of different size carried by said track, as set forth.

In witness whereof I have hereunto set my 55 hand in the presence of two subscribing witnesses.

WILLIAM A. MERRALLS.
